UNITED STATES PATENT OFFICE.

MILTON H. SPIELMAN, OF CLEVELAND, OHIO, ASSIGNOR TO THE DOMESTIC ELECTRICAL COMPANY, OF CLEVELAND, OHIO, A CORPORATION OF OHIO.

SWITCH-OPERATING MECHANISM.

1,356,663.

Specification of Letters Patent. Patented Oct. 26, 1920.

Application filed December 26, 1918. Serial No. 138,756.

To all whom it may concern:

Be it known that I, MILTON H. SPIELMAN, a citizen of the United States, residing at Cleveland, in the county of Cuyahoga and State of Ohio, have invented a certain new and useful Improvement in Switch-Operating Mechanism, of which the following is a full, clear, and exact description, reference being had to the accompanying drawings.

10 This invention relates particularly to mechanisms for operating the controlling switch of electrically driven portable devices. The essential object of the invention is to provide a simple, efficient mechanism 15 for operating a switch for such a device. A more specific object is to so arrange such mechanism that the switch may be automatically closed to start the motor when the handle of the device is brought to a position 20 for operating it, and be automatically opened to stop the motor when the handle is brought to a position of rest.

My switch operating mechanism is adapted for various portable devices of the character mentioned. A common illustration of such device is an electrically driven portable vacuum cleaner. Such a vacuum cleaner is ordinarily provided with a handle for moving the cleaner about the surface to be operated upon, the handle being usually pivoted to the frame and adapted to be swung from a vertical to a substantially horizontal position. Devices are provided for latching or otherwise holding the handle in its vertical position where it may stand when the cleaner is not in use, and when in use the handle is swung downwardly and operated at angles varying from a horizontal position to approximately seventy or eighty 40 degrees.

Features of my invention are that no attention need be given to the stopping and starting of the motor of the device, for the current is automatically shut off when the handle is brought to its substantially vertical position, at which the device is normally idle, and as soon as the handle is brought to a slight angle from the vertical, at which the device may be operated, the current is sent through the motor by the first movement of the handle closing the switch.

The switches for controlling the motors of portable vacuum cleaners, for example, are usually manually operable and are mounted at some point on the handle which

requires that the handle carry wires running up and down the same, and, as the handles are usually provided with a metal cap, there is considerable danger of the operator receiving electric shocks, whereas, 61 with my device, the switch may be mounted directly on the motor casing, and the handle may be entirely free from the electric wiring.

My invention is hereinafter more fully 65 described in connection with the accompanying drawings showing its embodiment in a portable vacuum cleaner, and the essential characteristics are summarized in the claims.

In the drawings, Figure 1 is a side elevation of a suction cleaner equipped with my invention, showing the parts in their idle position; Fig. 2 is a side elevation of the same illustrating the operative position; 75 Fig. 3 is an enlarged side elevation of the frame of such a cleaner showing the switch and operating device in position; Fig. 4 is a section on a still larger scale showing the means on the handle bail for operating the 80 switch, the latter being indicated in dot and dash lines; Fig. 5 is an edge elevation of the operating mechanism and switch; Fig. 6 is a section on the same plane as Fig. 4 looking in the opposite direction from that figure, showing the switch member in dot and dash lines; Fig. 7 is an axial section through the switch and its operating member; Fig. 8 is a detail view showing the 85 switch removed; Fig. 9 is a sectional detail 90 showing the device for latching the handle in different positions; Fig. 10 is a vertical section of the same; Fig. 11 is a horizontal section through the handle bail looking down on the latching device.

Referring to the drawings by the use of reference characters, 10 indicates the suction nozzle, 11 the fan chamber, and 12 the exhaust spout integrally connected and forming the cleaner frame which is mounted 100 on wheels 14 and 15. At 20 is indicated the motor housing mounted above the fan chamber, and at 22 is shown the dust bag connected with the exhaust spout and suitably attached at its opposite end to the handle 105 25.

The handle 25 is secured at its lower end to a U-shaped bail 26 normally straddling the motor housing 20 and pivoted by bolts 28 to the sides of the frame of the cleaner, 110

whereby the handle may swing about the axis of the bolts 28 from a substantially vertical position, where it is normally at rest, to varying operating positions, being frequently brought as low as a horizontal position to move the cleaner under furniture.

On one side of the cleaner frame is provided a device for latching the handle in various positions which is shown as comprising a segmental plate 18 held in position by one of the screws to which the handle is pivoted, and by a second screw 19 extending into a suitable lug. This segmental plate 15 is provided with an offset portion through which is provided a slot 21, the plate extending upwardly at 23 adjacent the slot and being notched, as at 24, to receive a latching pin 27 carried by the bail. The pin 20 27 extends through the bail and is vertically slidably in the slot 29 being held in the position given it by a flat spring 31. At 33 is provided a leaf spring secured to the segmental plate at its inner side and shown as 25 provided with a depression 37 adapted to engage a corresponding projection pressed from the handle bail.

To accomplish the object of this invention and cause the cleaning to start by starting the motor as soon as the handle is brought into operative position, I have provided the following switch operating device: Current is led to the motor within the housing 20 by wires in a suitable cable indicated at 30 35 which is connected through a suitable plug or snap terminal 32 at the side of the motor with wires 34 and 35 leading to switch terminals indicated at 36, current passing through one of the wires named being 40 passed through the motor by suitable terminal connections arranged preferably within the housing 20. A suitable switch member is provided for connecting the terminals 36 and is indicated at 38 as comprising a bridge 45 mounted on an extension of a rotary member 40 and having its ends adapted to bear against the terminal plates 36. The member 40 is shown as rotatably mounted in a switch block 42 made of suitable insulating 50 material. At the outer end of the rotatable member 40 is provided a non-circular stud or projection 48 which carries an actuator such as a disk 45 secured in place by a screw 44 extending into the member 40. The disk 45 is provided with a notch 50 adjacent which is an upwardly extending finger 52. An operating pin 54 is carried by one side of the bail 26 and normally projects into the notch 50, whereby the swinging 60 of the bail about the screws 28 causes a partial rotation of the disk 45 which turns the connecting bridge 38 from the position indicated in dot and dash lines in Fig. 8 to that shown in solid lines, closing the circuit 65 through the motor and starting the same.

The operating pin 54 is preferably carried on a slidable member 60 having its opposite ends engaging inwardly turned ears 62 of a plate 63 shown as adjustably secured to the side of the bail 26. A slot 64 embracing a bolt 65 holding the plate 63 in position permits vertical adjustment of this plate and operating pin so that the pin may be properly positioned with relation to the switch when assembling the device, after 75 which it may remain permanently set. The slide 60 is urged downwardly by a spring 66 until a shoulder 67 of the slide 60 abuts the lower ear 62. This slide and spring are provided to permit the pin to move upwardly over the edge of the disk 45 to again engage its notch, in case the switch disk becomes inadvertently turned out of its normal position with relation to the handle.

The disk 45 is shown as carrying an inwardly projecting finger 70 engaging a slot 72 in the switch block, limiting the oscillating movement of the disk. The switch block is shown as covered by a metallic casing 74 which is secured to the motor housing 20 by screws, the heads of which are indicated in Fig. 6, at 75.

The operation of my device is as follows: When not in operation the cleaner normally stands with the handle 25 in an upright substantially vertical position as shown in Fig. 1. To start cleaning the operator grasps the upper portion of the handle and lowers the same rearwardly, to push the cleaner about the surface to be operated upon, and this lowering movement swings the operating pin 54 rearwardly, engaging the rear side of the notch 50 turning the disk 45 which turns the connecting bridge 38 to close the circuit, thus starting the motor 100 and cleaning operation begins. Further downward movement of the handle causes the finger 70 to come to the end of its arcuate slot, whereupon the operating pin 54 passes out of the notch 50, while the disk 110 stands as thus turned where it may receive the pin on its return.

Upon stopping the cleaning operation either momentarily or otherwise, the handle is merely raised to its upright position 115 where the spring 33 latches it, allowing it to stand at rest. In this raising movement the operating pin 54, as it comes toward the disk 45, engages the projecting finger 52 of this disk, swinging the finger forwardly 120 and turning the disk to move the bridge 38 off from its contact plates, breaking the circuit through the motor and stopping the same. If it is desired to firmly latch the handle in its upright position so that it may 125 not be inadvertently dropped and result in closing the switch the pin 27 is moved downwardly to engage the proper notch 24 causing the secure latching of the parts, as the spring 31 engages the notch in the bail. The 130

other notches 24 in the segment plate may be used for latching the handle in other positions when desired.

It will be seen from the foregoing description that there are no unsightly wires on the handle 25; the switch mounted on the motor housing may be made very artistic; the operation is entirely automatic and needs no attention; the cleaning operation being started by merely grasping the handle and bringing it to operative position; the device is simple and effective; it has no parts liable to get out of order and is capable of being cheaply manufactured. The switch mechanism shown is merely illustrative of any form of switch which may operate by turning in one direction to close the circuit, while turning in the reverse direction opens the circuit.

Having thus described my invention, what I claim is:

1. The combination of a pivoted operating handle, an electric switch, said electric switch comprising a casing, a reciprocating contact member, an actuator outside the casing for operating said contact member, separated shoulders on the casing, and a projection carried by the actuator for engaging said shoulders to limit the movement of the actuator, a notch in the periphery of the actuator, an upward projection at one side of the notch, and a projection on the handle adapted to engage one side of said notch as the handle is swung from an upright to a slanting position and adapted to engage said upward projection when the handle is returned to its upright position, whereby the actuator may be moved to operate said contact member.
2. The combination of a pivoted operating handle, an electric switch, said switch comprising a casing, a reciprocating contact member, an actuator outside the casing for operating said contact member, a notch in the periphery of the actuator, an upward projection at one side of the notch, and a projection on the handle adapted to engage one side of said notch as the handle is swung from an upright to an inclined position, and adapted to engage said upward projection when the handle is returned to its upright position whereby the actuator may be moved to operate said contact member.
3. An electric switch for an electrically driven device having an operating handle, said switch having a reciprocating contact member, an actuator connected with said member and a separate member urged toward the actuator by spring action and moved with the handle to rotate the actuator as the handle is moved.
4. An electric switch for an electrically driven device having a pivoted operating handle, said electric switch having an oscillating

contact member, an oscillating actuator rigidly connected with said member and having separated shoulders, a projection adapted to engage said shoulders and movable with the handle as it swings about its pivot, and relatively movable with respect to the handle toward and away from said actuator, and a spring for urging said projection into position to engage said shoulders and thereby actuate the switch as the handle is moved.

5. An electric switch, for an electrically driven device having a pivoted operating handle, comprising an oscillating contact member, an actuator connected with said member having separated shoulders in its periphery, one of which extends radially a greater distance than the other from the periphery of said actuator, a lug carried by the handle adapted to engage one of said shoulders to rotate the actuator for opening said switch, and adapted to engage the other of said shoulders to rotate the actuator for closing said switch as the handle is moved.

6. An electric switch, for an electrically driven device, having a pivoted operating handle, comprising a casing, a reciprocating contact member, an actuator outside the casing for operating said contact member, separated shoulders on the casing, a projection carried by the actuator engaging said shoulders to limit the movement of the actuator, a notch in the periphery of the actuator, an upward projection at one side of the notch, and a projection on the handle adapted to engage one side of said notch as the handle is swung from an upright to a slanting position to close the switch, and adapted to engage said projection to open the switch when the handle is returned to its upright position.

7. The combination with an electrically driven device having a pivoted operating handle therefor, an electric switch, having a reciprocating contact member, an actuator connected with said member and having a notch in its periphery, a projection carried by the handle yieldingly urged toward the actuator and adapted to engage said notch to rotate the actuator when the handle is moved.

8. The combination of a pivoted operating handle, an electric switch, said switch comprising a casing, an oscillating contact member, an actuator rigidly connected with said contact member, stops fixed with relation to the casing, a projection carried by the actuator and engaging said stops whereby the movement of the actuator is limited, separated shoulders on the actuator, a projection on the handle adapted to engage one of said shoulders as the handle is swung from an upright non-operative position to its highest inclined operative position, and

- 4
- adapted to engage the other of said shoulders when the handle is returned to its upright position, whereby the actuator may be moved to operate said contact member.
- 5 9. The combination of a pivoted operating handle, an electric switch, said switch comprising a casing, an oscillating contact member, an actuator outside said casing connected with said contact member, a notch 10 in the periphery of the actuator, a peripheral projection in the plane of the actuator at one side of the notch, a lateral projection on the handle adapted to engage one side of said notch as the handle is swung from non-operative to its highest operative position to rotate the actuator and thereby close the switch, and adapted to engage said upward projection to rotate the actuator and open the switch when the handle is returned to its non-operative position.
10. The combination of a pivoted operating handle, an electric switch, said switch comprising a casing, a reciprocating contact member, an oscillating actuator outside said casing connected with said contact member, separated shoulders carried by said actuator, a spring pressed member slidably mounted on the handle and having a lateral projection adapted to engage one of said shoulders as the handle is swung from non-operative to an operative position to rotate said actuator and thereby close the switch, and adapted to engage the other of said shoulders to rotate the actuator and open the switch when the handle is returned to its non-operative position.
- 15 In testimony whereof I hereunto affix my signature.
- 20 MILTON H. SPIELMAN.
